UNITED STATES PATENT OFFICE.

JOSEPH E. BLAIN, OF TOLEDO, OHIO; ESTELLA H. BLAIN, ADMINISTRATRIX OF SAID JOSEPH E. BLAIN, DECEASED, ASSIGNOR, BY MESNE ASSIGNMENTS, TO ESTELLA H. BLAIN, OF THOMPSON, PENNSYLVANIA.

CONTAINER.

Application filed February 18, 1918. Serial No. 217,783.

To all whom it may concern:

Be it known that I, JOSEPH E. BLAIN, a citizen of the United States of America, residing at Toledo, Lucas County, Ohio, have invented new and useful Containers, of which the following is a specification.

This invention relates to cartons or containers, more particularly to the spout or opening means therefor.

10 This invention has utility when incorporated in containers for dry, granular or fragmentary materials, as smoking tobacco.

Referring to the drawings:

Fig. 1 is a medial section of a container in accordance with the invention herein, designed as a smoking tobacco box;

Fig. 2 is a perspective view of the device of Fig. 1, showing the initial movement of the closure toward open position;

20 Fig. 3 is a perspective view of the device with the spout or closure fully open, a portion being broken away;

Fig. 4 is a perspective view of the outer tube or main container of the device;

25 Fig. 5 is a perspective view of the inner tube or auxiliary container of the device; and

Fig. 6 is a perspective view of the trough-shaped closure for the device.

30 The outer wall providing tube of the container is shown as of rectangular form having the broader opposing side walls 1, 2, the connecting narrower walls 3, 4, and the fixed end closure or wall 5 remote from the 35 open end 6 of the tube. There is assembled in this outer tube, the auxiliary container having the side walls 7, 8, for disposal adjacent the walls 1, 2, and the connecting walls 9, 10, within the walls 3, 4. The 40 walls 7, 8, have the receding portions 11, from the fulcrum bearing points 12 at the open end of this inner tube. The wall 10 is short of extending to the receding portions 11, to provide the seat 14. The closure 45 15 for the open end 13 disposed within the opening 6, has the extensions 16, 17, approximating quadrant form, as sides for a trough or spout, normally acting to hold the closure assembled by coacting between 50 the double walls 1, 7, and 2, 8.

To facilitate filling assembly, the inner tube may have its end adjacent the closed end of the outer tube 5, closed. Under such

circumstances, the inner tube or auxiliary container, which, in the instance of tobacco, 55 may be paraffined to preclude evaporation of the contents, can have a bottom and be filled, the trough-shaped closure placed thereover, and this filled auxiliary container with its closure then assembled with the 60 outer tube or main container. With the tobacco box so assembled and filled, access thereto is readily obtained by depressing the axial portion of the quadrant closure to move the end 15 upon the fulcrum bearings 12 as an axis. This inward movement or tilting is permitted by the receding wall portions 11. This slight rocking of the closure to initiate opening, when the contents are loose, provides a desirable 65 spout for shaking out the desired quantity of the smoking tobacco. In those instances where it is desired to crowd the tobacco and work it together before removing a pipeful or other desired quantity, the spout may be rocked from the 70 position in Fig. 2 to the position shown in Fig. 3, where the extension 18 of the closure may swing into locked position in the seat 14. When the quantity has been 75 removed or poured from the spout, this spout 15, 16, 17, may be rocked back into closure forming position upon the fulcra 12 as an axis, with the quadrants guided between the double walls of the container 80 to the stop 19. There is accordingly only frictional holding of the closure in position, while it operates as a hinged member and may swing to a full open or definitely locked position. The device is one simply 85 assembled, with no parts to cause trouble in getting out of order, and has great conveniences in use.

What is claimed and it is desired to secure by Letters Patent is:

95 1. A rectangular container embodying an outer tubular portion forming a terminal opening, an inner tubular portion adjacent the opening providing a fulcrum spaced from the container corners, and a closure 100 having extensions between said walls, said closure being tiltable on the fulcrum in movement from closed to open position independently of shifting the container contents as held by the inner walls by closure 105 movement.

2. A container embodying an outer wall forming an opening, an inner wall for the container providing a fulcrum adjacent the opening, and a closure for the opening rockable on the fulcrum in movement from closed to open position independently of shifting the container contents as held by the inner walls by closure movement, said closure having parallel extensions operable between said walls in closure movement co-acting with the fulcrum intermediate the length of the extensions at the opening.
3. A container provided with outer walls having an opening, a pair of opposing inner walls providing a fulcrum bearing adjacent said opening, and a trough-shaped closure rockable intermediate of the trough portion extent on the bearing in movement from open to closed positions, the sides of said trough being operable between said walls as guideways for the closure independently of shifting the container contents as held by the inner walls by closure movement.
4. A container provided with outer walls having an opening, a pair of opposing inner walls having a portion receding from the opening to form a seat, and a trough-shaped closure tilttable into said seat in movement from closed to open position, the sides of said trough being operable between said walls as guideways for the closure.
5. A tubular container having double side walls, a portion of the inner walls receding, and a closure for the container end, said closure having a pair of extensions entering between the double side walls at the receding portion, whereby the closure may be rocked into the receding portion to throw the portion of the closure remote therefrom outward in opening the closure.

In witness whereof I affix my signature.

JOSEPH E. BLAIN.
